UNITED STATES PATENT OFFICE

2,446,127

ADJUSTABLE STOOL

Richard R. Cramer, Dayton, Ohio

Application July 6, 1944, Serial No. 543,673

4 Claims. (Cl. 155—94)

1

This invention relates to stools of the type adapted for the seating of a person. Such stools comprise a seat member and supporting means therefor and are commonly used by draftsmen to sit at drafting tables, by housewives in the kitchen, by clerks and cashiers behind counters and cash registers in mercantile establishments, and in various other circumstances.

The primary object of the invention is to provide a stool of the type referred to wherein the seat member is capable of being very rapidly raised and lowered relative to its supporting means by a simple "finger-tip" operation.

Another object is to provide a stool of the above type in which the seat member can be raised by simply lifting up thereon and the seat member will automatically remain in any position to which it is raised.

A further object is to provide a stool of the character described in which the seat member can be lowered to any position by operation of a finger-tip control so designed that when the same is engaged by the hand of the user the seat member may be rapidly lowered, and, when the user disengages his hand from the control, the seat member will remain in the position which it occupies at such time.

Another object is to provide a stool of the type referred to, in which a control member is carried by the seat member in a location conveniently engageable by the hand of the user as he grasps the seat member to move the same relatively to the supporting means.

Another object is to provide a stool of the above type including fluid pressure means constructed and arranged to support the seat member with respect to the supporting means upon a confined body of fluid, and valve means operative to permit additional fluid to enter the confining space as the seat member is raised while normally preventing the fluid from passing out of said confining space so as to maintain said seat member in the position to which it is raised.

Another object is to provide control means operable to condition the valve means referred to, in such a manner as to permit the fluid to pass out of the aforesaid confining space and thereby allow the seat member to be lowered.

Another object is to provide a stool of this type of generally improved construction which is simple and inexpensive to manufacture.

Other objects, advantages, and features of the invention will become apparent from the following detailed description, taken in conjunction with the accompanying drawing, in which:

2

Figure 1 is a vertical sectional view illustrating a preferred embodiment of my invention.

Figure 2 is an enlarged detail sectional view through the piston and cylinder, showing the valve means.

Figure 3 is an enlarged detail sectional view showing a portion of the control means.

Figure 4 is an enlarged detail sectional view showing the positive locking means and the limit stop detent means.

Now referring to the drawing, the stool there illustrated comprises a seat member A which may be of wood or any other suitable material, and supporting means therefor generally designated by the letter B and comprising legs 2, four of which are provided and suitably joined together to provide a rigid supporting frame structure. As illustrated, the legs 2 may be conveniently formed of metal tubing, the tubular legs 2 being bent adjacent their upper ends which extend through suitable openings provided in the annular flange 3a of a flat ring-like member 3. The legs 2 may be welded or otherwise secured to the flange 3a.

Metal tubes 4 each have one end welded or otherwise secured to a respective leg 2 adjacent the lower end of the latter. The other end of each tube 4 may extend through a suitable opening provided in the annular flange 5a of a disc member 5, the tubes 4 being welded or otherwise secured to flange 5a. An annular tube member 60 may extend around and be welded or otherwise secured to the legs 2, as shown, to further assist in providing a rigid frame structure.

Fluid pressure means is provided including co-operating piston and cylinder elements associating the seat member A with the supporting means B for relative movement of said seat member A toward and away from said supporting means B.

To this end, a cylinder 6 has its lower end secured to the disc 5. For this purpose, the plug 7, force fitted into the cylinder 6, is secured to disc 5 by bolt 8. The upper end of the cylinder 6 extends through the ring 3 and is threaded as at 6a for cooperation with corresponding threads on the nuts 9 and 10 which clampingly engage the ring 3 and thereby rigidly secure the upper end of cylinder 6 thereto.

The piston element generally designated by the numeral 11 works in the cylinder 6 and comprises a gland 12 of leather or like material clamped between members 13 and 14 which are secured together by means of bolts or screws 15. The member 14 is force-fitted into the lower end of sleeve 16 which slidably fits in the cylinder 6.

and serves to connect the piston element 11 with the seat member A, whereby the seat member A is firmly supported upon the supporting means B for upward and downward movement relative thereto. For securing the seat member A to the sleeve 16, the latter is threaded at its upper end as at 16a for cooperation with the correspondingly internally threaded boss 17a of a plate 17 which is secured to the seat member A by means of screws 18.

The cylinder 6 is adapted to have fluid confined therein and, for this purpose, a liquid 50, such as oil or the like commonly employed in hydraulic devices, is availed of. The nut 10 carries a flexible sealing member 19 of leather or like material tightly fitting around the sleeve 16 to prevent leakage of fluid from the cylinder 6. This fluid fills any space interiorly of the cylinder 6 below the piston 11 and is also contained within the interior of the sleeve 16 above the piston 11.

Valve means is provided which is normally operative to prevent movement of fluid from the interior of the cylinder 6 below piston 11 to the interior of sleeve 16 above piston 11 while permitting movement of said fluid from the interior of sleeve 16 above piston 11 to the interior of cylinder 6 below piston 11 as the seat member A is raised relative to the supporting means B. Control means is provided which is operable to condition the valve means for movement of fluid from the interior of cylinder 6 below piston 11 to the interior of sleeve 16 above piston 11 as seat member A is lowered relative to the supporting means B.

To the foregoing ends the member 13 is provided with a central bore 13a registering with a central opening in the member 12 and a central bore 14b in the member 14 which has passages 14a communicating with its central bore 14b, whereby to provide a continuous passage for the fluid through the piston 11 between the interior of cylinder 6 below piston 11 and the interior of sleeve 16 above piston 11. The lower end of bore 13a is provided with a seat for receiving the ball valve member 20 (located in a recess 13b at the lower end of member 13) for closing the passage through the piston 11. Ball valve member 20 is free to move off its seat and away from bore 13a due to pressure of fluid moving downwardly therethrough during raising movement of the seat member A relative to the supporting means B. Under such conditions, the ball valve member 20 is retained in association with piston element 11 by impingement of ball 20 with pins 21 secured to member 13 and extending transversely across the recess 13b at the lower end of member 13. Normally, however, the ball valve member 20 is maintained seated in bore 13a by the pressure of fluid confined in the cylinder 6 below the piston 11, thus automatically maintaining the seat member A in any position to which it is raised relative to supporting means B.

The control means for the valve member 20 includes an actuating member or rod 22 the lower end of which (Figure 2) is slidably received in the central bore 14b of the member 14. The lower extremity 22a of rod 22 is of reduced diameter to permit movement of fluid through the passage in piston 11 when ball 20 is unseated. The upper end of rod 22 slidably extends through the bore of a plug 23 force-fitted into the upper end of sleeve 16. Rod 22 is biased upwardly to the position shown in the drawings (see Figures 1, 2, 3) by means of spring 24 engaging washers 25 and 26 slidably mounted on rod 22, washer 25 being

retained on rod 22 by nut 27 threaded onto rod 22. Plug 23 carries a flexible sealing member 28 of leather or like material closely fitting around the rod 22 to prevent leakage of fluid from sleeve 16.

The control means also includes a cam member 29 secured to rod 30 associated with plate member 17 for sliding movement relative thereto. Rod 30 is biased in a rightward direction, as shown in Figures 1 and 3, by means of spring 31 engaging an abutment 32 secured to rod 30. The latter is provided with a handle or finger engaging portion 30a arranged under the seat member A and adjacent the edge thereof so that said handle may be conveniently engaged by the hand of a person while grasping the seat A to lower the same.

A detent member 35 is movable in a bore provided in a collar 34 secured to the cylinder 6, said detent 35 being movable through an opening provided in cylinder 6. Detent 35 is biased rightwardly (see Figure 4) into engagement with sleeve 16 by spring 36 engaged by set screw 31. Sleeve 16 is provided with an annular recess 38 (Figure 2) cooperable with detent 35 to limit the upward movement of sleeve 16 and piston 11 upon engagement of detent 35 in recess 38. The pressure fluid preferably fills the space in the cylinder 6 below piston 11 and the interior of sleeve 16 at least to a height above the point of highest movement of piston 11 as determined by the limiting engagement of detent 35 with sleeve 16. Recess 38 is formed with a tapered shoulder 38a providing cam means to disengage detent 35 from recess 38 upon downward movement of seat member A and sleeve 16 relative to supporting means B.

Positive locking means is provided comprising a hand screw 40 threaded into collar 34. The inner end 40a of screw 40 extends through an opening in cylinder 6 and is engageable with sleeve 16 to positively prevent relative movement between sleeve 16 and cylinder 6 if desired. This locking means is an added provision for locking the seat member in position, said locking means not being essential for the purpose of maintaining seat member A in raised position, since the fluid pressure means is designed to operate to automatically prevent downward movement of the seat member until the valve means is properly conditioned by the control means as hereinafter described.

In operation, the user of the stool of the invention may raise the seat member A relative to the supporting member B by engaging the seat member A with his hand and lifting or pushing the same upwardly. At the same time the supporting means B may be held firmly, although this is not essential since the weight of the supporting means B will exert a downward force thereon tending to draw the supporting means B away from the seat member A upon the application of a lifting force to the latter. As the seat member A is raised relative to supporting member B, the sleeve 16 (secured to the seat member A) and the piston element 11 (associated with sleeve 16) are raised relative to cylinder 6 which is secured to supporting means B. This upward movement of piston 11 and sleeve 16 allows ball 20 to be displaced from its seat, thereby opening the passage through piston 11 so that fluid may move from the interior of sleeve 16 above the piston 11 to the interior of cylinder 6 below piston 11.

Such movement of the fluid will continue as long as the seat member A is being raised relative to supporting means B, detent 35 being cooperable with recess 38 at the lower end of

sleeve 16 to limit the upward movement of the latter. The seat member A is automatically maintained, at substantially the position to which it is raised, by the pressure of the fluid 50 in the cylinder 6 below the piston 11, which pressure forces the ball 20 to its seat, closing the passage through piston 11 and preventing movement of fluid therethrough from the interior of cylinder 6 below the piston 11.

When it is desired to lower the seat member A, the control handle 30a is engaged to pull rod 30 and cam member 29 in a leftward direction (Figure 3) causing cam 29 to engage nut 27 thereby pushing actuating rod 22 downwardly. This causes the lower extremity 22a of rod 22 to engage ball 20 moving the same downwardly, off its seat, thereby opening the passage through piston 11. When the control handle 30 is being so actuated, the seat member A may be pushed downwardly relative to supporting means B by hand pressure downwardly exerted upon seat member A, since such actuation of control handle 30 permits movement of fluid from the interior of cylinder 6 below piston 11, through the passage in piston 11 to the interior of sleeve 16 above piston 11, thereby allowing piston 11 and sleeve 16 to move downwardly relative to cylinder 6, as downward pressure is applied to seat member A. When the hand is disengaged from control handle 30a, cam 29 is biased to the position shown in Figure 3, out of engagement with nut 27 so that rod 22 is returned upwardly, by spring 24, out of engagement with ball 20 permitting the latter to be returned to its seat (by the pressure of fluid in cylinder 6 below piston 11), thus preventing further downward movement of seat member A relative to supporting means B.

It will be apparent from the foregoing that the raising of the seat member A may be effected practically by the fingers of the user's hand pressing upwardly on the underside of the seat member A. Likewise, the lowering of the seat member A may be effected practically by the application of the pressure of the user's thumb to upper side of the seat member A, adjacent the edge thereof, while a finger of the same hand engages the handle 30 to move it leftwardly, referring to Figure 3.

If desired, a spring can be provided engaging the pins 21 (or other supporting means) and the ball 20 to bias the latter to its seat, closing the passage through the piston 11. In such event, the control handle 30a would have to be actuated for both raising and lowering of the seat member A. The construction as above described without such spring is considered advantageous, since it does not require actuation of control handle 30a for raising movement of the seat member A.

Having thus described my invention, what I claim as new and desire to secure by Letters Patent is:

1. An article of furniture of the class described, comprising, in combination, a movable seat member, and stationary supporting means therefor, cooperating piston and cylinder elements, one of said elements being secured to said movable member and the other of said elements being secured to said supporting means, said piston element having a passage therethrough, said cylinder having fluid therein adapted to support the piston in the cylinder, a single valve member carried by said piston and adapted to close said passage and thereby prevent the flow of said fluid therethrough to the space above said

piston when the latter is at rest in said cylinder, said valve member being freely movable toward and away from closed position and being automatically movable to open said passage upon

5 upward movement of said piston in said cylinder whereby to permit fluid above said piston to flow through said passage to the space in said cylinder below said piston, and control means operable to hold said valve member in open position for movement of fluid through said passage from below the piston to the space in the cylinder above the piston for effecting lowering movement of said movable member relative to the supporting means, the control means comprising an actuating member movable in the direction of piston movement and operable to move the valve member to open position, means biasing said actuating member to non-actuating condition, a pull rod associated with the said movable member for transverse movement relative thereto, a cam member on said rod and engageable with said actuating member to effect operation of the valve member as aforesaid when the rod is pulled in one direction, and means 10 biasing said pull rod to a position in which the cam member is out of engagement with the actuating member.

2. An article of furniture of the class described, comprising, in combination, a movable seat member, and stationary supporting means therefor,

30 cooperating piston and cylinder elements, one of said elements being secured to said movable member and the other of said elements being secured to said supporting means, said piston element having a passage therethrough, said cylinder having fluid therein adapted to support the piston in the cylinder, a single valve member carried by said piston and adapted to close said passage and thereby prevent the flow of said fluid there-

35 through to the space above said piston when the latter is at rest in said cylinder, said valve member being freely movable toward and away from closed position and being automatically movable to open said passage upon upward movement of

40 said piston in said cylinder whereby to permit fluid above said piston to flow through said passage to the space in said cylinder below said piston, and control means operable to hold said valve member in open position for movement of fluid through said passage from below the piston to the space in the cylinder above the piston for effecting lowering movement of said movable member relative to the supporting means, said passage including a main portion extending ax-

45 ally through the piston and a branch portion extending at an angle thereto and communicating therewith and extending to the upper side of the piston, and wherein the control means comprises an actuating rod entering the main portion of

50 said passage to coat with the valve, the upper portion of the lower end of said rod entering the main portion of said passage having substantially the same diameter as said main portion whereby the rod is guided for upward and down-

55 ward movement thereby, the lower portion of said rod coating with the valve being of reduced diameter to a point above the point of communication of the main passage with the branch passage, whereby the reduced portion of the rod will not obstruct flow of fluid through the lower portion of the main passage and through said branch passage.

3. An article of furniture of the class described, comprising, in combination, a movable seat member, and stationary supporting means therefor,

cooperating piston and cylinder elements; one of said elements being secured to said movable member; and the other of said elements being secured to said supporting means, said piston element having a passage therethrough, said cylinder having fluid therein adapted to support the piston in the cylinder; pin members extending transversely across the piston member directly below the lower end of said passage; a valve member carried by said piston and freely movable between the lower end of said passage and said pins, the pins being arranged to coact with the valve member to limit movement of the valve member to movement between a position in which the valve member engages said pins and a position in which the valve member closes said passage to thereby prevent the flow of said fluid therethrough to the space above said piston when the latter is at rest in said cylinder, said valve member being automatically movable downwardly by gravity into engagement with said pins to open said passage upon upward movement of said piston in said cylinder whereby to permit fluid above said piston to flow through said passage to the space in said cylinder below said piston, and control means operable to hold said valve member in open position for movement of fluid through said passage from below the piston to the space in the cylinder above the piston for effecting lowering movement of said movable seat member relative to the supporting means.

4. An article of furniture of the class described, comprising, in combination, a movable seat member, and stationary supporting means therefor, cooperating piston and cylinder elements, one of said elements being secured to said movable seat member, and the other of said elements being secured to said supporting means, said piston element having a passage therethrough, said cylinder having fluid therein adapted to support the piston in the cylinder, pin members extending transversely across the piston member directly below the lower end of said passage; a ball valve member carried by said piston and freely movable between the lower end of said passage and said pin members, the lower end of said passage forming a valve seat for said valve member; the pins

being arranged to coact with the valve member to limit movement thereof to movement between a position in which the valve member engages said pins and a position in which said valve member engages said valve seat to close said passage to thereby prevent flow of fluid therethrough to the space above said piston when the latter is at rest in said cylinder, said valve member being automatically movable downwardly by gravity into engagement with said pins to open said passage upon upward movement of said piston in said cylinder whereby to permit fluid above said piston to flow through said passage to the space in said cylinder below said piston, and control means operable to hold said valve member in open position for movement of fluid through said passage from below the piston to the space in the cylinder above the piston for effecting lowering movement of said movable member relative to the supporting means.
